PACKAGE

Theodore V. Quarnstrom, Cleveland, Ohio, assignor to The American Steel and Wire Company of New Jersey, a corporation of New Jersey

Application December 8, 1933, Serial No. 701,517

13 Claims. (Cl. 206—46)

This invention relates to the packaging of long pieces, such as bale ties, one of the objects being to provide a package which may be manually made up and which will not come apart during handling or shipping. Other objects may be inferred.

The accompanying drawings illustrate packages embodying the features of the present invention, the various figures being as follows:

10 Figure 1 shows one form of a complete package. Figures 2 through 4 show one of the ends of this package in varying forms of completeness.

Figures 5 and 6 show the other end of this package, likewise in varying forms of completeness.

15 Figures 7 through 11 show another form of package in varying forms of completeness, Figures 9 through 11 showing the ends in completed form.

20 Figure 12 shows a further modification.

Referring to these drawings, bale ties 1 are bunched with their looped ends together to form a group. These looped ends make one end of the group larger than the other, it being assumed that the ties each consist of a straight length of wire with a loop formed at only one of its ends. A flexible covering 2 is over the large end of this group, and a short strand of wire 3 encircles the group over this covering 2, its ends being intertwined to fasten them together.

25 A long strand of wire 4 has an end fastened to those of the strand 3 by being intertwined with them. This strand 4 extends over the end of the group of ties and the covering 2, and back beside the group with spaced portions forming half hitches 4^a holding the latter together.

The covering 2 has a portion 2^a doubled back on itself over the short strand 3, and a short strand of wire 5 encircles the group over this doubled portion 2^a and the long strand 4, the ends of this strand 5 being also intertwined to fasten them together. This strand 5 is arranged between the strand 3 and the extreme end of the group of bale ties. Its intertwined ends may be hammered flat against the package. One of the functions of this strand 5 is to hold the strand 4 close beside the group, this being advantageous because of the large size of this end.

30 Another short strand 6 is looped about a portion of the bale ties 1 forming the group, and then encircles the latter as a whole, its ends being fastened by intertwining. This strand 6 is adjacent the small end of the group, and the other end of the long strand 4 is intertwined with its ends to provide a fastening. A flexible cover-

ing 7 is also over this end of the group, one of the bale ties 1^a projecting through this covering 7 and being bent double thereover. This helps anchor the covering 7 in place.

5 Further short strands of wire 8 and 9 encircle the covering 7 and the group of bale ties, these strands being respectively arranged to either side of the strand 6, and the strand 9 passing over the doubled portion of the tie 1^a. The ends of these last mentioned strands are respectively 10 intertwined and hammered flat against the package.

It is obvious how the package described may be manually made up, the various steps being indicated by the order of the figures of the drawings.

15 In the other form of package illustrated by the drawings, a flexible covering 10 is over the large end of the group of bale ties. A single long strand of wire 11 has a looped end portion 11^a 20 encircling the group over the covering 10 and extending therefrom over the end of the group and back beside the latter with spaced portions forming half hitches 11^b holding the group together. The looped portion 11^a may be fastened 25 by making an adjacent loop 11^c which is intertwined with the end of the strand 11, these intertwined portions being then hammered flat.

The covering 10 has a portion 10^a doubled back on itself over the looped portion 11^a of the strand 11, one of the half hitches 11^b being arranged 30 between the portion 11^a and the extreme end of the group to hold this double portion in place.

Another flexible covering 12 is over the small 35 end of the group, another one of the half hitches 11^b also serving to hold this covering in place. A portion 12^a of this covering is also doubled back, and the strand 11 extends over this end of the group and this covering, a looped portion 11^d 40 encircling the group, the doubled portion of the covering 12 and the strand 11 itself. This looped portion may be formed in a manner generally similar to that described in connection with the other end, the resulting intertwined parts being 45 likewise hammered flat.

It is also obvious how this last described package may be made up, the figures relating thereto likewise showing the various steps necessary.

50 The flexible coverings mentioned throughout the specification may consist of suitably shaped pieces of burlap. Half hitches are so well known that it is not considered necessary to describe their formation in detail. They may be likened to an overhand knot wherein the looped portion 55

of the same encircles the group to be held together.

Although the packages shown consist of ties having single loops, it is obvious that it is immaterial whether the ties have loops in one or both ends or whether the loops are grouped together or not.

All the half hitches so far shown are made by passing the strand of wire under and over itself so that locking results. However, Figure 12 shows this modified in that the strand is passed over and under itself so that slipping half hitches result.

Since the knotted portions of the strands are more apt to rust than the undeformed tie wires, this accelerating rusting of the latter, the strands holding the packages together may advantageously be rust-proofed in some manner.

I claim:

20. 1. A package including the combination of a group of long pieces and a strand arranged beside said group with spaced portions forming half hitches holding the same together.

25. 2. A package including the combination of a group of long pieces and a strand arranged substantially parallel and proximate said group with spaced portions forming half hitches holding the same together.

30. 3. A package including the combination of a group of long pieces, a covering over an end of said group, means for holding said covering in place and a strand connecting with said means, said strand extending over said end of said group and said covering and back beside said group with spaced portions forming half hitches holding the latter together.

35. 4. A package including the combination of a group of long pieces, a covering over an end of said group, a short strand encircling said group over said covering with its end interfastened and a long strand having an end fastened to the ends of said short strand, said long strand extending over said end of said group and said covering and back beside said group with spaced portions forming half hitches holding the latter together.

40. 5. A package including the combination of a group of long pieces, a flexible covering over an end of said group, means for holding said covering in place, a strand having an end connecting with said means and extending over said end of said group and said covering and back beside said group with spaced portions forming half hitches holding the latter together, said covering having a portion doubled back on itself over said means, and means for holding the doubled portion of said covering over the first named means and for holding said strand closely beside said group.

45. 6. A package including the combination of a group of long pieces, a flexible covering over an end of said group, a short strand encircling said group over said covering with its ends interfastened, a long strand having an end fastened to the ends of said short strand and extending over said end of said group and said covering and back beside said group with spaced portions forming half hitches holding the latter together, said covering having a portion doubled back on itself over said short strand, and a second short strand encircling said group over the doubled portion of said covering and said long strand, and having its ends interfastened.

70. 7. A package including the combination of a

group of long pieces, a covering over an end of said group and a strand having a looped end portion encircling said group over said covering and extending therefrom over said end of said group and said covering and back beside said group with spaced portions forming half hitches holding the latter together.

75. 8. A package including the combination of a group of long pieces, a flexible covering over an end of said group and a strand having a looped end portion encircling said group over said covering and extending therefrom over said end of said group and back beside said group with spaced portions forming half hitches holding the latter together, said covering being doubled back on itself over said looped end of said strand and one of said half hitches being arranged to hold this doubled portion thereover.

9. A package including the combination of a group of long pieces, a long strand arranged beside said group with spaced portions forming half hitches holding the same together and a short strand looped about a portion of the pieces forming said group and encircling the latter adjacent one of its ends with its ends and an end of said long strand interfastened.

10. A package including the combination of a group of long pieces, a long strand arranged beside said group with spaced portions forming half hitches holding the same together, a short strand looped about a portion of the pieces forming said group and encircling the latter adjacent one of its ends with its ends and an end of said long strand interfastened, a flexible covering over said end of said group and said short strand, one of said pieces forming said group having a portion projecting through said covering and bent double thereover, a second short strand encircling said group over said covering and the bent portion of said piece with its ends interfastened, and a third short strand encircling said group over said covering with its ends interfastened, said second and third short strands being arranged to either side of the first mentioned short strand.

45. 11. A package including the combination of a group of long pieces, a strand arranged beside said group with spaced portions forming half hitches holding the same together and a flexible covering over an end of said group, one of said half hitches encircling said covering and the latter being doubled back thereover, and said strand extending over said end of said group and said covering and having a looped portion encircling said group over the doubled portion of said covering.

12. A package including the combination of a group of long pieces, a flexible covering over an end of said group, a short strand encircling said group over said covering with its ends interfastened, a long strand having an end fastened to the ends of said short strand and extending over said end of said group and said covering and back beside said group with spaced portions forming half hitches holding the latter together, said covering having a portion doubled back on itself over said short strand, a second short strand encircling said group over the doubled portion of said covering and said long strand, and having its ends interfastened, a third short strand looped about a portion of the pieces forming said group and encircling the latter adjacent the other of its ends with its ends and the other end of said long strand interfastened, a flexible covering over said last named end of said group.

and said third short strand, one of said pieces forming said group having a portion projecting through said covering and bent double there-over, a fourth short strand encircling said group over said last named covering and the bent portion of said piece with its ends interfastened and a fifth short strand encircling said group over said covering with its ends interfastened, said fourth and fifth short strands being arranged to either side of said third short strand.

10 13. A package including the combination of a group of long pieces, a flexible covering over an end of said group and a strand having a looped end portion encircling said group over said covering and extending therefrom over said end of

said group and back beside said group with spaced portions forming half hitches holding the latter together, said covering being doubled back on itself over said looped end of said strand and one of said half hitches being arranged to hold this doubled portion there-over, a flexible covering over the other end of said group, another one of said half hitches encircling said last named covering and the latter being doubled back there-over, and said strand extending over said last named end of said group and said last named covering and having a looped portion encircling said group over the doubled portion of said covering.
